(57) **CLAIM**

The ornamental design for a mosaic solar cell, as shown and described.

DESCRIPTION

FIG. 1 is a top perspective view of a mosaic solar cell showing our new design;

FIG. 2 is a top plan view of the mosaic solar cell of FIG. 1;

FIG. 3 is a bottom plan view thereof;

FIG. 4 is a front elevation view thereof;

FIG. 5 is a rear elevation view thereof;

FIG. 6 is a left side elevation view thereof; and,

FIG. 7 is a right side elevation view thereof.

The broken lines shown in the drawings illustrate portions of the mosaic solar cell that form no part of the claimed design.

1 Claim, 3 Drawing Sheets
